CONSTRUCTION OF SHIPS

Leonard Newham, Flushing, N. Y., assignor of
one-half to H. W. Roeloffzen, New York, N. Y.

Application December 27, 1941, Serial No. 424,565

8 Claims. (Cl. 114—66.5)

This invention relates to new and useful improvements in the construction of ships, and the principles involved herein are applicable to all types of mercantile marine vessels, such as freighters, as well as to naval vessels, and patrol boats alike.

The advantages of my improved construction are many, as will appear from the discussion hereinafter set forth and forming the preface to the actual disclosure of my construction of boats for which this application for patent is made.

Thus, one of the advantages of my said construction lies in that an increased speed, increased stability, and an easy maneuverability are obtained of the ship; this, of course, is due mainly to the unique construction of the hull of said ship, in regard to which the bottom construction below the waterline consists of a double concavity extending from the bow and cut-water to one-third of the length of the boat from the bow; this double concavity flows into one concavity, lateral to the rock of the chines; while the arc of the longitudinal concavity runs level with the water on the bow and stern. The rear or stern part of the bottom from one-third from the stern to the stern of the longitudinal concavity runs in a downward direction, so that when the boat is at high speed the water flowing along the longitudinal concavity causes the stern of the boat to rise, with the result that the boat planes level with the water, which consequently increases the speed and decreases the drag.

As the center of buoyancy in my construction is farther forward than in the conventional hulls, and the center of gravity low, these features will contribute to keep and maintain a good balance of the boat on the sea at high as well as low speeds.

The bottom of the hull consists of two concavities, of which one is lateral and the other longitudinal.

Among other features, specific to my construction in some cases (such as war vessels), may be mentioned that the boat has no portholes on the outside. The said boat is streamlined, and has a runway or recess in the center of the deck extending downwardly towards the stern; this latter construction is of special importance, when it concerns a naval vessel or patrol boat, as it enables the depth-charges to roll into the water from the aft of the boat.

The boat, as constructed, has no external keel, but it has an internal keel forming part of the interior construction of said boat, and running from stem to stern; this keel does not, however,

come in contact with the water as in conventional boats.

In said conventional boats the hull pivots on the center of the keel, which is the center of the hull; therefore, in said boats as the speed increases the stability decreases.

In my construction of a hull the keel is internal, and does, as formerly said, not come in contact with the water; it serves, however, greatly to strengthen the internal construction of said boat.

It may in this connection be noted that in my construction the two chines will act as two keels, whereby the phenomenon arises that with the increase in speed the stability is also increased instead of decreased.

It may further in this connection be stated that the said keel arrangement increases the stability about 50% in a boat, constructed according to my invention, over that of the conventionally built boats; the reason for this is that the chines are below the center of the hull, which causes the latter to have full contact with the water at the extreme beam of the hull; the said stability will always remain constant.

My construction, as set forth, embodies what may be termed a double concavity, one on the port—and one on the starboard side of the cut-water. The double concavities start at the bow and descend to the rock of the chines. These two concavities cause the bow of the boat to cushion on the water, forming an air-cushion between the water and the boat. Consequently they reduce the pounding of the boat at high speed. These two concavities flow into one concavity at about one-third of the length of the boat from the bow, which is the rock of the chines, the latter concavity is called the longitudinal concavity, as it runs from one-third of the length from the bow continuous to the stern. The arc of this longitudinal concavity starts lateral to the rock of the chines and ends at the stern and is parallel with the water at these two points. The rear and stern part of this concavity, which thus runs from one-third from the stern to the stern, slopes in a downward direction, so that when the boat is going at high speed the water flowing along this longitudinal concavity causes the stern of the boat to rise, releasing the water fan-wise, which, by the way, is the only wash the boat has at high speed, with the result that the boat planes level with the water, which action will consequently increases the speed, decrease the drag, and reduce the suction of the propeller, increasing at the same time the stability.

A lateral concavity is constructed between the two rising chines, from the rock of the chines, one-third from the length of the bow to the stern, and acts in conjunction with the longitudinal concavity in giving the boat great stability on the water and making an easy flow for the discharge of the water from the stem to stern.

The lateral concavity is so constructed that it changes from a double concavity at the bow to a single concavity ending at the stern, which construction serves to stabilize the boat and to dispose easily of the flow of water under the hull in order to overcome resistance.

The chines are located at the extreme beam of the hull, one on the port and one on the starboard side, running the full length of the boat from bow to stern; thus said chines act as skates, balancers and protectors of the center of the boat. They will increase the seaworthiness and stability of the boat, and in conjunction with the bottom construction of the lateral and longitudinal concavities make the performance and maneuverability of the boat at slow and high speed very easy and effective.

The combination of the above mentioned three novel features of construction has not as yet ever appeared in the construction of any ship.

The rising chines on the boat in the water should be of great importance in the construction of, for instance, coast guard boats, as they have a beneficial influence upon the steering ability of the boat; they are placed in an important position on the boat and cover three important points, namely, that the rock of the chines is one-third from the length of the boat from the bow; the deepest draft is one-third from the length of the boat from the bow, and the widest beam is one-third of the length of the boat from the bow.

The chines run from one-third of the length of the boat from the bow in an upward direction toward the end of the stern of the boat, where they run flush with the lateral and longitudinal concavities.

The chines acting as fortifiers as to the construction of the boat serve as stabilizers of the latter in the water; thus, they are practically the skates on which the boat rides, while at the same time they are the protectors of the ship's bottom.

Through the bottom construction of the lateral and longitudinal concavities together with the rising chines the boat is of shallow draft, and is easily handled in rough or congested water; when built as a freighter it is safe from torpedo attack through its shallow draft, maneuverability and speed.

The boat will have two air-vents in the center of the longitudinal concavity extending in an angular direction to the deck at one-third of the length of the boat from the stern to release the vacuum accumulated under the boat.

In order to give, if possible, a more full understanding of the operation of the principles of my construction, it may be further stated, that while the boat is going at high speed, the water built up in the lateral concavity, and thus forming a column of water, will serve as the boat's keel, and tend to increase the stability.

The purpose of the longitudinal concavity is to the effect that when the boat is under way, the water enters the double concavity on either side of the cut-water, which will cause the bow to rise; the water, then, enters the main concavity, which is the longitudinal concavity; and, as the water passes the center of the longitudinal concavity, the pressure of the water is then built up to such

a degree that it reduces the suction of the propellers, thereby causing the stern to rise, and the excessive water to pass out fan-wise at the latter, thus lending added stability to the rear of the hull; thus, when the boat is under way, the hull will rest on the four extreme points, that is, port and starboard, bow and stern, which will give the full purchasing power on the water at all times.

With the above and other objects in view, this invention consists of the novel features of construction, combination and arrangement of parts, hereinafter fully described, claimed and illustrated in the accompanying drawings forming part of this specification, and in which similar characters of reference indicate corresponding parts in all views, and in which:

Figure 1 is a side elevational view, showing a boat with my improved construction.

Figure 2 is a top plan view of the same.

Figure 3 is a section taken through the said boat on the lines 7—7 and showing the port-holes.

Figure 4 is a section on the lines 4—4 of Figure 3.

Figure 5 is a diagrammatic sectional view on the lines 5—5 of Figure 1.

Figure 6 is a diagrammatic sectional view on the lines 6—6 of Figure 1.

Figure 7 is a diagrammatic sectional view on the lines 7—7 of Figure 1; while

Figure 8 is also a diagrammatic sectional view on the lines 8—8 of Figure 1.

Referring more particularly to the drawings, the numeral 15 indicates a boat, in general, having a bow 16, and a stern 17. In the forward section of said boat is indicated a control room at 18; while a motor room is indicated at 19, from which latter the shaft 20, with the propeller 21, is driven. The numeral 22 indicates a steering mechanism; one being in the control room, while a second one is located at the control room hatch 23, which latter, when opened, serves as a flying bridge.

The boat is constructed with an internal keel 30, of a suitable design. In the construction, as shown, said keel starts at the bow of the boat, having a triangular cross section, as at 31, which cross section changes into an I-beam, as may be seen at 32.

Side-sills or "chines" 33 are formed along the lower sides of the boat and extending the entire length of the latter.

The keel 30 and the chines 33 constitute or form the back-bone of the boat; the frames are of a concave shape at the bottom, running lateral from the keel to the chines, and then upwardly on a substantially vertical plane. The boat may also be provided with bulkheads (not shown) in the conventional manner.

From the cabin to the stern of the boat is provided a run-way 34 sloping downwardly towards said stern. This run-way may be used as a gang-way as well as a discharging means for depth bombs, etc.

The run-way 34 is provided with the railing 35 of any conventional construction.

As may be noted from the drawings, no port-holes are provided for at the outside of the hull; said portholes are constructed inside of the run-way 34, as may be seen at 36 in Figures 3 and 4.

The rock of the chines, indicated at 45, is one-third of the length of the boat from the bow, and is the point, where the two longitudinal concavities 46 and 47 join to form one longitudinal concavity 48.

The double longitudinal concavities 46 and 47

descend from the bow 16 to the rock 45 of the chines 33, where they merge into one concavity 48, which may be termed the longitudinal concavity; at said rock of the chines the latter concavity then rises again slightly, beginning subsequently to descend again before it reaches the point 24, which is one-third of the length of the boat from the stern, continuing to descend towards said stern.

This construction will consequently bring a larger body of water under the hull amidship between the said rock of the chines and the point, located as said before, one-third of the length of the boat from the stern, which body of water will be discharged or disposed of in a fan-wise manner, while it at the same time will supply the propeller with a great flow of water, and incidentally have the effect of rising the stern of the boat.

In order to avoid air pockets to form in the concavities, which condition would be detrimental to the operation of the boat, air vents 49 are provided for, connecting the concavity 48 with the ventilators 50.

As shown in the drawings W indicates the water line.

Torpedo tubes T are arranged at the stern of the hull, and are placed at water-line level, so that a low center of gravity and an easy access to the water are obtained.

These tubes are so placed that they run parallel with the center-line of the hull, thereby assuring more accuracy as to hits.

At the same time the outer surfaces of the tubes, which project at the water line, will act as stabilizers for the stern and maintain the balance of the torpedoes as they are discharged from said tubes.

The undersides of the tubes which project beyond the sides of the hull at the stern, are shaped so as to conform with the shape of the hull.

It is obvious that minor changes may be made in the construction and arrangement of parts, within the scope of the appended claims.

What I claim as new and desire to secure by Letters Patent of the United States is:

1. In the construction of a ship, a hull, the bottom of the latter having a double concavity extending from the bow to one-third of the length of the hull, said double concavity merging substantially at that point into a longitudinal concavity extending all the way to the stern of the hull, and a lateral concavity extending transversely of the bottom of the hull from the aforementioned point to the stern of said hull.

2. In the construction of a ship, a hull, the bottom of the latter being provided with a double concavity extending from the bow, one on the port, and one on the starboard side, to one-third of the length of the hull from the bow, said concavities merging into a longitudinal and a lateral concavity at said point, or at the rock of the chines, and both of said latter concavities extending to the stern, the longitudinal concavity having an upward curvature with its highest point one-third of the length of the hull from the stern, substantially as shown and described.

3. In the construction of a ship, a hull, the bottom of the latter being provided with a double

concavity extending from the bow, one on the port, and one on the starboard side, to one-third of the length of the hull, said concavities merging into a longitudinal and a lateral concavity one-third of the length of the hull from the bow, or at the rock of the chines, and both concavities extending to the stern, the longitudinal concavity having an upward curvature with its highest point one-third of the length of the hull from the stern, the arc of said longitudinal concavity starting lateral to the rock of the chines and ending at the stern.

4. In the construction of a ship, a hull, the bottom of the latter being provided with a double concavity extending from the bow, one on the port, and one on the starboard side, to one-third of the length of the hull, said concavities merging into a longitudinal and a lateral concavity one-third of the length of the hull from the bow, or at the rock of the chines, and both of said latter concavities extending to the stern, the longitudinal concavity having an upward curvature with its highest point one-third of the length of the hull from the stern, chines formed upon each side of the boat and extending the full length of the latter.

5. In the construction of a ship, a hull, the bottom of the latter being provided with a double concavity extending from the bow, one on the port, and one on the starboard side, to one-third of the length of the hull, said concavities merging into a longitudinal and a lateral concavity one-third of the length of the hull from the bow, or at the rock of the chines, and both of said latter concavities extending to the stern, the longitudinal concavity having an upward curvature with its highest point one-third of the length of the hull from the stern, chines formed upon each side of the boat and extending the full length of the latter, said chines extending from the greatest width of the hull and below the center of the latter rearwardly in an upward direction toward the end of the stern, and being flush with said lateral and longitudinal concavities at said stern.

6. In the construction of a ship, a hull, the bottom of the latter being provided with a double concavity extending from the bow, one on the port and one on the starboard side, to one-third of the length of the hull, said concavities merging into a longitudinal and a lateral concavity one-third of the length of the hull from the bow, or at the rock of the chines, and both of said latter concavities extending to the stern, the longitudinal concavity having an upward curvature with its highest point one-third of the length of the hull from the stern, chines formed upon each side of the boat and extending the full length of the latter, said chines sloping downwards from the bow and rising towards the stern.

7. In an invention, as claimed in claim 2, and wherein the hull is provided with an internal keel.

8. A ship's hull having a double concavity, one on each side of the cutwater, and each one extending from the bow to one-third of the length of said hull, said double concavity merging at that point into a longitudinal and lateral single concavity extending to the stern.

LEONARD NEWHAM.
